UNITED STATES PATENT OFFICE.

DE WITT C. KING, OF LOS ANGELES, CALIFORNIA.

PLUNGER-PUMP.

1,190,772.

Specification of Letters Patent. Patented July 11, 1916.

Application filed July 21, 1913. Serial No. 780,173.

To all whom it may concern:

Be it known that I, DE WITT C. KING, a citizen of the United States, residing at the city of Los Angeles, in the county of Los Angeles and State of California, have invented new and useful Improvements in Plunger-Pumps, of which the following is a specification.

My invention relates more particularly to 10 a plunger pump for pumping deep oil wells. In pumping deep oil wells it is very desirable that the flow of oil through the plunger shall be as free as possible and that on the downward movement of the plunger that it 15 shall freely fill with oil. When the plunger carries a packing to make the joint between it and the pump barrel a working fit the size of the plunger must be reduced to accommodate the rings thereby diminishing 20 the internal diameter of the plunger.

It is the object of my invention to produce a deep well pump especially adapted for pumping oil wells in which there shall be an increased internal diameter in the 25 plunger thereby producing a maximum flow of liquid therethrough and to provide a plunger for use with the Garbutt attachment for removing the standing valve in which the flow of oil through the plunger shall not 30 be diminished by said attachment.

To that end the essential feature of my invention is the construction of a pump barrel in two sections with the lower section of a greater diameter than the upper section, 35 in combination with a plunger which has a working fit in the upper section without the use of any packing and is provided with a Garbutt attachment for raising the standing valve when desired, whereby the 40 entrance to and flow of oil through the plunger is not interfered with by said attachment and a maximum flow of oil through the plunger is permitted. I accomplish this object by the pump described herein and 45 illustrated in the accompanying drawings forming a part hereof in which:

Figure 1 is a side elevation partly in section of my improved pump. Fig. 2 is a section on the line 2—2 of Fig. 1 with parts 50 in elevation.

In the drawings 5 is the upper section of the pump barrel which I will distinguish from the lower section by calling it the lift section. To the lower end of the lift section 55 is screwed the lower section 6 of the pump barrel which I distinguish from the

upper section by calling it the filling section. In the pump barrel is mounted the hollow plunger 7 which is provided at its upper end with valve cage 8 in which is 60 mounted valve 9. To the top of the cage is secured the operating rod 10. In the bottom of the plunger is screwed the usual pierced Garbutt plug 11 through which passes the stem 12 of the Garbutt attachment for removing the standing valve and cage 13 which is secured to the lower end of the filling section of the pump barrel in the usual well known manner. In the sides of the plunger above plug 11 are a plurality 70 of long narrow slots 14 which with the opening through the plug are of a slightly greater area than the cross internal area of the plunger above the slots.

The lift section of the pump barrel is of 75 a length that on the up stroke of the plunger the slots in the plunger do not come into the lift section of the barrel and on the down stroke of the plunger the top of the plunger does not go quite to the bottom of the lift 80 section. The filling section of the pump barrel is of a sufficiently larger diameter than the lift section to permit enough oil to surround the plunger on its downward stroke and enter the slots in the sides of the 85 lower end of the plunger which with the opening through the Garbutt plug will furnish oil to freely fill the plunger. The length of the sections of the pump barrel is governed by the stroke desired. 90

By making a working fit between the lift section of the barrel and the plunger I do away with all packing rings and am able to make the opening through the plunger larger than if packing rings were provided. 95 By making the diameter of the filling section of the pump barrel larger than the lift section and by providing slots in the lower end of the side wall of the plunger, the plunger freely fills and thereby a pump of 100 increased capacity over one using packing rings is provided and at a less cost.

Having described my invention what I claim is:

1. In a deep well pump the combination 105 of a pump barrel, composed of a lift section and a filling section, the filling section having a greater diameter than the lift section; a tubular plunger having slots in the side walls thereof near its bottom, said plunger 110 having a working fit in the lift section and a clearance in the filling section; a valve

- cage secured to and at the top of said plunger; a valve in said valve cage; a pierced tubular plug secured in the bottom of said plunger below the slots therein; a standing valve secured to the bottom of the pump barrel; and a Garbutt attachment secured to said standing valve and having the stem of said attachment passing through the plug in the bottom of the plunger.
- 10 2. In a deep well pump the combination of a pump barrel, composed of a lift and a filling section, the filling section having a greater diameter than the lift section; a tubular plunger having slots in the side walls thereof near its bottom, said plunger having a working fit in the lift section and a clearance in the filling section; a valve cage secured to and at the top of said plunger; a

valve in said valve cage; a pierced tubular plug secured in the bottom of said plunger 20 below the slots therein; a standing valve secured to the bottom of the pump barrel; and a Garbutt attachment secured to said standing valve and having the stem of said attachment passing through the plug in the 25 bottom of the plunger, a clearance being provided between the stem and plug for the passage therebetween of liquid.

In witness that I claim the foregoing I have hereunto subscribed my name this 10th 30 day of July, 1913.

DE WITT C. KING.
